UNITED STATES PATENT OFFICE

162,595

AIR-DRIVEN FLOOR POLISHER

William T. Theis, North Hollywood, and Leland W. Green, Malibu, Calif., assignors to Interstate Engineering Corporation, El Segundo, Calif., a corporation of California

Application August 12, 1950, Serial No. 11,742

Term of patent 14 years

(Cl. D9—2)

To all whom it may concern:

Be it known that we, William T. Theis and Leland W. Green, citizens of the United States and residents of the city of North Hollywood and Malibu, respectively, county of Los Angeles, State of California, have invented a new, original, and ornamental Design for Air-Driven Floor Polisher, reference being had to the accompanying drawing, forming a part hereof, in which:

Fig. 1 is a plan view of an air-driven floor polisher showing our new design;

Fig. 2 is a side elevational view;

Fig. 3 is a front elevational view;

Fig. 4 is a rear elevational view; and

Fig. 5 is an inverted plan view thereof.

We claim:

The ornamental design for an air-driven floor polisher, substantially as shown.

WILLIAM T. THEIS.
LELAND W. GREEN.
